(57) **CLAIM**

The ornamental design for a portable power station, as shown and described.

DESCRIPTION

FIG. 1 is a perspective view of a portable power station, showing my new design;

FIG. 2 is a front elevation view thereof;

FIG. 3 is a right-side elevation view thereof;

FIG. 4 is a rear elevation view thereof;

FIG. 5 is a left-side elevation view thereof;

FIG. 6 is a bottom plan view thereof; and,

FIG. 7 is a top plan view thereof.

The broken lines in the drawings are for the purpose of illustrating portions of the portable power station that form no part of the claimed design.
